CORRUGATED LOAF OF BREAD

William R. Kauffman, Jr., York, Pa., assignor to J. S. Hershey Baking Company, York, Pa., a corporation of Pennsylvania

Filed Oct. 14, 1963, Ser. No. 76,955

Term of patent 14 years

(Cl. D8—1)

Fig. 1

Fig. 2

Fig. 3

FIG. 1 is a side elevation of a corrugated loaf of bread, showing my new design.

FIG. 2 is an end elevation thereof.

FIG. 3 is a fragmentary corner view thereof taken in the direction of line 3—3 of FIG. 1 showing more clearly the corrugations.

The essential features of my design reside in a cylindrical loaf of bread provided on its entire cylindrical surface with alternate helical ridges and grooves adjacent to each other and extending from end to end of said loaf at a substantial angle to the axial center line thereof, together with a projecting, rounded ridge extending around the loaf diametrically across its ends, thus dividing the loaf into substantially equal semi-cylindrical halves, all as shown.

I claim:

The ornamental design for a corrugated loaf of bread, substantially as shown and described.
